UNITED STATES PATENT OFFICE.

FRANK W. REYNOLDS, OF MANSFIELD, OHIO.

STOVE-DOOR.

1,157,041.

Specification of Letters Patent. Patented Oct. 19, 1915.

Application filed December 4, 1912. Serial No. 734,815.

To all whom it may concern:

Be it known that I, FRANK W. REYNOLDS, a citizen of the United States of America, residing at Mansfield, in the county of Rich-
5 land and State of Ohio, have invented cer-
tain new and useful Improvements in Stove-
Doors, of which the following is a specifi-
cation.

The present invention relates to stove
10 doors, and more particularly to those stove
doors wherein an inner partition or lining
is provided in order to more perfectly break
the communication of the hot air on the in-
side, with the cold air on the outside of the
15 door. It is well known that in the manu-
facture of stove doors and especially oven
doors, that it is very desirable to provide
the door with a lining of the character in-
dicated, as the heat radiation through the
20 door is thus greatly reduced with a conse-
quent saving of heat and fuel.

Another very desirable feature in the con-
struction of oven doors, and especially the
25 type of oven doors commonly known as drop
oven doors, is to have the lining flush with
the inside face or edge of the door and so
arranged that when the oven is open, the
door will present a perfectly smooth plane
30 surface directly in line with the bottom of
the oven, and will therefore serve as a shelf
onto which receptacles, such as baking pans,
etc., may be slid into and from the oven,
without the necessity of lifting or without
35 any jarring or jolting of the pans, thus
greatly reducing the danger commonly called
falling, in the art of baking cakes, etc.

Numerous methods have heretofore been
employed for securing the lining in place,
one of the most common being by means of
40 through-going bolts or screws which are usu-
ally threaded into bosses provided for that
purpose on the inner surface of the door.
These bosses not only materially increase the
weight of the door, but the drilling and tap-
45 ping of the same necessitates considerable
labor thus largely augmenting the cost of
the completed door.

The principal object of the present in-
vention is therefore to provide an improved
50 stove door of the character indicated, in
which the lining and the exposed edges of
the walls of the door will form a perfectly
smooth, plane surface, and in which the lin-
ing can be easily and quickly placed in posi-
55 tion without the use of screws or bolts, there-
by reducing the weight of the door as well

as the labor necessary to secure the lining
in place, and consequently the cost of manu-
facturing the completed door.

The above and other objects are attained 60
by the construction and arrangement of
parts hereinafter fully described, and illus-
trated in the accompanying drawings, in
which:

Figure 1 is a vertical sectional elevation 65
of the preferred form of my improved door.
Fig. 2 is a perspective view of the lining
formed, ready to be sprung into position in
the door. Fig. 3 is a perspective view of
70 the door, the usual hinge-lugs, handle and
latch being omitted. Fig. 4 is a view of a
portion of a modified form of the lining,
and Fig. 5 is a sectional elevation of the
75 door with the modified form of lining in
position.

Referring more specifically to the draw-
ings, reference numeral 1 indicates a stove
80 door, the walls 2, back 22, (and other parts
not shown,) of which may be of the ordinary
and well known construction. On the inner
sides of the walls 2 I provide a series of
85 lugs 3 and 4, which (as will be seen in Fig.
3) are tapered inwardly and downwardly
from a point near the upper edge of the
walls 2, thus forming the shoulders or pro-
jections 5. At a convenient distance below
90 an imaginary horizontal line connecting the
bottom surfaces of the lugs 3 and 4, and
preferably midway between the said lugs,
I provide a similar inverted lug 6 forming
95 the projection 7. While I have shown and
described two upper lugs 3 and 4, and one
lower inverted lug 6 in each wall 2 of the
door, yet it will be apparent that any con-
venient number of lugs may be used, the
100 number so used being proportioned to the
size of the door.

A lining 8 is provided, with the down-
wardly projecting flanges 9, as shown in
105 Fig. 2, these flanges having provided there-
in the apertures 10 and 11, which are posi-
tioned in corresponding relation to the lugs
3 and 4; the said apertures 10 and 11 being
adapted to engage the lugs 3 and 4 respec-
tively, when the lining 8 is in the assem-
bled position as shown by Fig. 1.

The lining 8 is preferably formed from
thin sheet-metal, and it will therefore be
apparent that, as it is being placed in posi-
tion in the door, the lower edges 12 of the
110 flanges 9 will slidably engage the tapered
surfaces of the lugs 3 and 4 and the lower

edges 12 will be converged, that is to say, they will be crowded inwardly until the lining has been forced to the proper depth in the door, when the apertures 10 and 11 will engage the lugs 3 and 4 respectively, and by reason of the resiliency of the material from which the lining 8 is made, the flanges 9 will diverge or spring outward against the inner surfaces of the walls 2 of the door, as shown in Fig. 1, and the projections 5 will thus securely retain the lining in position.

When the lining 8 has been placed in position, as just described, the projections 7 of the lugs 6 will serve as stops to prevent the lining from being forced deeper into the door, and thus a smooth or even surface of the inner side of the completed door is maintained.

It will be noticed by referring to Fig. 2, that the ends 13 of the flanges 9 are cut away at their lower edges 12, that is to say they are beveled back from their intersection at the corners 14 to the lower edges 12, and it will be apparent that this is necessary, in cases where the flange portions 9 are made the full length and width of the lining, in order that the flanges 9 may properly clear each other at the corners of the door when they are converged by engagement with the tapered lugs 3 and 4 while the lining is being placed in position in the door.

In the modification shown in Figs. 4 and 5, the flange portions 9^a are formed so as to conform, in their normal position, substantially to the tapered surfaces of the lugs 3 and 4. The lower portions of the flanges 9^a have provided thereon the laterally projecting rib or flange 15, formed substantially parallel to the body portion 16, and substantially corresponding in width to the projections 5 of the lugs 3 and 4.

It will be obvious that the manner of placing the modified form of lining in position in the door is similar to that of the preferred form hereinbefore described, the only difference being that the lining is held in position by the engagement of the upper surface 17 of the flange or rib 15 with the projection 5 of the lugs 3 and 4.

While I have shown and described my invention as applied to a particular form of stove door, yet I wish to reserve the right to make such modifications therein as will properly fall within the scope of the appended claims.

Having thus fully described my inven-

tion, what I claim and desire to secure by Letters Patent is:—

1. In a stove door, the combination of a series of lugs forming lateral projections on the inner surface of the walls thereof, the said lugs being tapered from a point adjacent the upper edge of the said walls to the said projections, a second series of lateral projections formed below the first mentioned series, and a lining having flanges formed thereon, said flanges having cut away portions at each end thereof, and being provided with a series of apertures adapted to engage the first mentioned series of projections, the lower edge of the said flanges being adapted to engage the said second mentioned series of projections, substantially as, and for the purpose set forth. 75

2. A stove door comprising a back, side walls and end walls, a plurality of inwardly projecting, tapered lugs on the inner surface of said walls, a lining having flanges formed thereon, said flanges being cut away at each end thereof, and being adapted to engage said lugs, the exposed edges of said walls and the lining forming a smooth plane surface, substantially as described. 80

3. A stove door comprising a back, side walls and end walls, a series of lugs forming lateral projections on the inner surface of said walls, a lining having flanges formed thereon, said flanges being cut away at each end thereof, and being provided with a series of apertures adapted to engage the said projections, the inner surface of said walls and said lining forming a perfectly smooth plane surface, substantially as described. 90

4. A stove door comprising side walls and end walls, a series of lugs forming lateral projections on the inner surface of said walls, the said lugs being tapered from a point adjacent the upper edge of the said walls to the said projections, a lining having flanges formed thereon, the said flanges being cut away at each end thereof and being provided with a series of apertures adapted to engage the said projections, the said lining and upper edge of said walls forming a smooth plane surface, substantially as described. 100 105

In testimony whereof I affix my signature in presence of two witnesses.

FRANK W. REYNOLDS.
